UNITED STATES PATENT OFFICE

139,898

DESIGN FOR AN AIRPLANE

Perry Walker, Kansas City, Mo.

Application January 3, 1944, Serial No. 112,165

Term of patent 3½ years

(Cl. D71—1)

To all whom it may concern:

Be it known that I, Perry Walker, a citizen of the United States, residing in Kansas City, county of Jackson, and State of Missouri, have invented a new, original, and ornamental Design for an Airplane, of which the following is a specification, reference being had to the accompanying drawings, forming part thereof.

Figure 1 is a side elevational view of an airplane showing my new design;

Figure 2 is a top plan view;
Figure 3 is a bottom plan view;
Figure 4 is a front elevational view; and
Figure 5 is a rear elevational view.

I claim:

The ornamental design for an airplane, as shown.

PERRY WALKER.
